SANITARY BED

Catherine B. Kane, Greenwich, Conn.

Application September 30, 1938, Serial No. 232,537

4 Claims.

(Cl. 5—91)

This invention relates to beds for invalids, infants, and the like, and aims to provide improvements in such beds whereby complete toilet accommodations are provided for the occupant so as to avoid the necessity of the occupant leaving the bed.

In general, the invention aims to provide such a bed which will remain dry over a long interval, and whose essential parts may be turned over, or, other words, reversed, so as to present new and clean upper surfaces, the interval of use of these parts without requiring cleaning being thereby doubled.

The above and other objects will become apparent in the description below, in which characters of reference refer to like-named parts in the accompanying drawing.

Referring briefly to the drawing,

Figure 1 is a plan view of the mattress.

Figure 2 is a side elevational view of the mattress and the boxes which provide a support for the former.

Figure 3 is a fragmentary cross-section taken on the line 3—3 of Figure 1.

Figure 4 is a plan view of the above-mentioned boxes, partly in section and having parts broken away.

Figure 5 is an end view of Figure 4.

Referring in detail to the drawing, the numeral 10 represents the mattress which is provided with a plurality of spaced-apart openings 11 which pass through the same from the top to the bottom of the mattress. At the center the mattress is provided with a similar but substantially larger opening 12. In the form of mattress illustrated, i. e., a coil spring mattress, the openings 11 pass through the enclosures of the coils 13. The outer shell of the mattress, as well as the linings of the openings 11 and 12, are properly formed of any suitable waterproofed material.

The bedstead, or frame, has not been shown in the drawing, as a complete understanding of the invention may readily be had without complicating the drawing unnecessarily by showing the bedstead. The mattress 10 is supported on a plurality of aligned boxes 14, 15, 16, whose combined area is equal to that of the mattress, and through the upper and lower horizontal walls of which openings 17 are provided, the latter being in vertical alignment with the holes 11 of the mattress when the latter is mounted on the boxes. The boxes are set directly upon the bedstead, not shown. Central large openings 18 are provided in the top and bottom walls of the middle box 15,

which, likewise, lie directly under the large opening 12 through the mattress.

The end box 14 has in its end wall 19 a narrow horizontal slot 20, and in its opposite end wall 21 a wide slot 22, the upper edge of the slot 22 lying above the upper edge of the slot 20 and the lower edge of the slot 22 lying below the lower edge of the slot 20. A corrugated sheet of card board or other suitable inexpensive material 23, whose corrugations or channels 24 extend from the end wall 19 toward the other end wall 21, is slidably mounted in the box 14 by inserting the same through the slot 20. Its length is such that, when pushed in all the way so that its outer edge rests on the base of the slot 20, its inner edge extends beyond the slot 22, with the board 24 being supported on the base of the slot 22 along a line adjacent and parallel to the said outer edge of the board. If desired, to facilitate withdrawal of the board 23 through the slot 20 and to prevent the outer edge of the board from falling through the slot 20, any suitable means such as tongues 25 may be provided on the outer edge of the board. The other end box 16 is identical but complementary construction as the box 14.

The middle box 15 has a slot 26 and 27 in its end walls 28 and 29, respectively, each of these slots being of the same dimensions as the wide slots 22 of the end boxes 14 and 15. The box 15 is further provided with a horizontal slot in one of its other vertical walls (although such slot may be provided in both of said other vertical walls), through which a receptacle or pan 31 may be slid in or out of the box 15, the pan being adapted to rest on the floor of this box. It is to be noted that the edges of the boards 23 protrude into the enclosure of the pan.

The center opening 12 of the mattress is provided with an hourglass-shaped lining 32 of zinc or other suitable strong but slightly yieldable material, the center of which has a peripheral bead 33 formed therein, extending into the opening through the lining 32. The opening 12 is provided for the excretion of feces by the occupant, who may be seated at that time on a separate annular cushion having a depending internal flange 35. The latter, when the occupant is seated on the cushion, will be forced downward by his weight into the lining 32, and the bead 33 serves as a limit stop to the downward movement of the flange 35 to prevent the cushion from being forced too far into the opening 12. Feces which are thus passed will fall into the pan 31.

The passing of fluid excreta by the occupant is

done through any of the openings 11. The surfaces of the mattress surrounding the openings 11 may be rounded, if desired. Such fluid excreta will fall through the holes 17 onto the board 23, 5 which will catch the same and by gravity pass it through the slots 22-26 into the pan.

When it is desired to reverse the mattress and the boxes, the pan is first removed, and both the mattress and the boxes 14, 15 and 16 are turned 10 upside down, with the fresh former bottom surface of the mattress now on top and with the former bottom surfaces of the boxes now providing the top surfaces thereof on which the mattress rests. In the said reversing of the boxes, 15 the boards 23 will have turned on their outer ends (in the slots 20) as a pivot, so that their inner ends will in the reversed position rest against what was formerly the top edge of the slot 22 but is now the bottom edge; thus, the inclination of the boards 23 toward the center box, 20 and, hence, toward the pan, will be the same as before.

Obviously, modifications in form and structure may be made without departing from the spirit of 25 the invention.

I claim:

1. In a bed, means for supporting a perforated mattress comprising a plurality of hollow boxes mounted side by side and having a combined 30 area equal to the area of the mattress, said boxes having openings through their top and bottom walls, said boxes constituting a middle box and two end boxes, said middle box having a wide slot through each of its end walls, said end boxes 35 each having a wide slot through its inner end wall aligned with one of said middle box slots and a narrow slot through its outer end wall, boards slidably mounted in said end boxes and insertable through said end wall slots thereof, said boards 40 having their inner ends resting on the lower edges of their said wide inner wall slots and projecting into said middle box, and a removable pan mounted on the floor of said middle box.

2. In a bed, reversible boxes adapted to support 45 a perforated mattress, said boxes being placed end-to-end and comprising a middle box and a pair of end boxes the combined area of which is substantially equal to that of said mattress,

said middle box having a removable pan therein, each of said boxes having a corrugated board slidably mounted therein, said end boxes having means for tilting said boards toward said center box when said boxes are in upright or reversed 5 position, said boxes having their top and bottom walls perforated.

3. In a bed, means for supporting a perforated mattress comprising a pair of reversible end boxes and a middle box therebetween, said middle box 10 having wide slots in its end walls adjacent said end boxes, said end boxes having slots of the same width as said first-named slots on their inner walls adjacent said first-named slots and narrow slots in their outer walls, a corrugated board slidably supported in each of said end boxes between 15 the lower edges of said narrow slot and said wide slot of said end box, said lower edge of said wide slot of said end box lying below said upper edge of said end slot thereof, the upper edge of 20 said wide slot of said end box lying above the upper edge of said narrow slot thereof, said board thereby sloping toward said middle box, said end boxes upon being turned upside down causing said boards to slope in the same direction, 25 the top and bottom walls of said boxes being perforated.

4. In a bed, means for supporting a perforated mattress comprising a pair of end boxes and a middle box therebetween, said middle box having 30 wide slots in its end walls adjacent said end boxes, said end boxes having slots of the same width as said first-named slots on their inner walls adjacent said first-named slots and narrow slots in their outer walls, a corrugated board slidably supported in each of said end boxes between the lower edges of said narrow slot and said wide slot of said end box, said lower edge of said wide slot of said end box lying below said upper edge of 35 said end slot thereof, the upper edge of said wide slot of said end box lying above the upper edge of said narrow slot thereof, said board thereby sloping toward said middle box, said end boxes upon being turned upside down causing said 40 boards to slope in the same direction, the top and bottom walls of said boxes being perforated, and tongues on the outer edges of said boards.

CATHERINE B. KANE.
